UNITED STATES PATENT OFFICE

WILLIAM MARCROFT, OF CRANSTON, AND JOHN A. MOLLOY, OF APPONAUG, RHODE ISLAND, ASSIGNEES TO UNIVERSAL WINDING COMPANY, OF BOSTON, MASSACHUSETTS, A CORPORATION OF MASSACHUSETTS

CREEL

Application filed July 14, 1928. Serial No. 292,672.

This invention relates to creels for holding cops, cones or packages of yarn, thread or the like to deliver the strand material therefrom in various processes of the textile art.

One object of the invention is to provide an improved creel adapted to support a plurality of nonrotatable cops, cones or packages to adapt the strand material to be drawn off over the end thereof at a high rate of speed without interference from ballooning and with a uniform tension on all of the ends. Another object of the invention is to provide a creel in which the supplies are closely associated to economize in space while permitting free access to the cops and their holders for convenience in piecing up the ends and in creeling and doffing.

Another object of the invention is to provide a creel wherein the strand-governing or separating means may be swung out of the way to permit access to be had to the supply-holders for the purpose of creeling and doffing, and in piecing up.

Further objects of the invention are, in general, to provide a creel from which the yarn, thread or other strand material may be warped or transferred at high speed while at the same time delivering the ends under a more constant and uniform tension to improve the quality of the finished product.

The present invention may be embodied in a creel having a form of construction such as described in the following specification and illustrated by way of example in the accompanying drawings. In the drawings:

Fig. 1 is a front elevation of the improved creel shown as embodied in a preferred form of construction, duplication of the parts being omitted for the sake of clearness;

Fig. 2 is an end elevation of the creel structure shown in Fig. 1;

Fig. 3 is an enlarged plan view of a portion of the creel showing the strand-governing means or separators in both operative and inoperative position;

Fig. 4 is a diagrammatic view illustrating

the manner of creeling and doffing the cops or packages; and

Fig. 5 is an enlarged perspective view of one of the strand-governing devices or separators used on the creel.

In delivering yarn, thread and other strand material from non-rotatable cops or other supply packages the resistance to the draft on the strands varies considerably at different points in the delivery. When the cops or supply packages are full, the strands deliver with comparatively little resistance owing to the relatively large diameter of the package and the considerable amount of yarn contained in each coil unwound therefrom; while, as the package is reduced in diameter, the coils contain much less yarn and consequently must uncoil much faster. This increase in the speed of unwrapping of the coils throws the yarn outwardly under the action of centrifugal force, producing what is termed ballooning.

For the purpose of controlling the delivery of the ends from the creel under a constant tension, the yarns are guided through tension-devices. Due to the high speed at which the ends deliver from the cops, the amount of ballooning is such that frequently the strands are thrown out or released from the tension-devices and become entangled in the projecting parts of the creel. As one feature of the present invention, the creel is provided with means adapted to minimize the extent of ballooning of the strands and thereby prevent entanglement of the yarns, such means being so constructed that when it is necessary to piece up the ends or to doff and re-creel the supplies, the strands adjacent thereto may be separated or parted and the separators themselves moved out of the way to give access to the supplies and their holders.

Referring first to Figs. 1 and 2 of the drawings, the preferred form of construction of the creel as herein illustrated comprises a framework or grill constituted by vertical rods or uprights 11 and 12. The rods 11 and 12 may be supported in socketed feet 13 mounted on a suitable base 14 bearing casters 15 which permit the creel to be

5 moved about as a unit over the floor. The rods or uprights 11 and 12 are arranged in parallel relation in two opposite series spaced a short distance apart, the several uprights in each row being connected by horizontal tie-rods or longitudinal stringers 16 which pass through suitable bearings or brackets 17 secured to the upper ends of the uprights.

10 The two spaced grills of the framework are connected at the top by cross-braces 18 having clamps 19 at the ends of their arms embracing the tie-rods 16 and clamped thereto by bolts or other means. The uprights 11 may be braced from the base 14 by inclined struts 20, the lower ends of which are received in sockets 21 fixed to the base 14, while their upper ends are fastened to the laterally-projecting arms of brackets 22 mounted on the tie-rods 16. Preferably, the struts 20 are provided at each end of the framework as shown in Fig. 1.

15 As shown in Fig. 2, the rearward uprights 11 of the frame are of heavier construction than the forward rods 12, being adapted to support the supply-holders 23 for the cops or packages which are preferably in the form of cross-wound cones C. The cones C may be wound on suitable cop-tubes or yarn-receivers which are slid onto the supply-holders 23 and retained in place by suitable means as usually employed for this purpose. Preferably, the supply-holders 23 are tilted upwardly so that the weight 20 of the cones tends to hold them in place thereon.

25 In the present construction the supply-holders 23 are arranged in pairs to support two cones from a single bracket 24. As illustrated in Fig. 3, the bracket 24 has a central recessed portion adapted to be clamped around the upright 11 by means of a U-bolt 25. The looped portion of the bolt 25 engages around the rod 11 opposite to the side engaged by the recessed portion of the bracket 24. The arms of the bolt 25 pass through spaced openings in the bracket 24 and projecting therebeyond are threaded for the reception of nuts 26 which are 30 screwed snugly against the bracket to draw the parts together.

35 The manner of mounting the brackets 24 on the uprights 11 is such that they may be adjusted vertically on the creel to locate the supply-holders 23 in proper relation with respect to their associated tension-devices or other strand-guiding means through which the yarns draw. It will be noted from Figs. 1 and 2 that the supply-holders 23 are arranged on the uprights 11 in parallel rows, the construction of the brackets 24 and the spacing of the uprights 11 being such that the cones C are uniformly spaced apart both vertically and horizontally. The use of duplex supply-holders for the pairs of cones

40 C reduces the number of uprights 11 required and provides that the supplies may be mounted close together, thereby increasing the capacity of the creel while economizing in space.

45 In the present construction the creel is shown as provided with tension-devices 30 for controlling the delivery of the strands of yarn or thread unwinding from the cones C. However, it will be understood that means other than those herein illustrated 50 may be employed for tensioning the strands delivering to the warping machine or other apparatus used for the purpose of converting the material carried by the creel. The tension-devices 30 are preferably mounted in pairs on the smaller forward rods 12 of the creel frame. In the form as herein shown the tension-device 30, illustrated in detail in Fig. 3, comprises a pair of disks 55 31 mounted on a pin or stud 32 projecting upwardly from a bracket 33. The bracket 33 is provided with a central hub 34 adapted to embrace the rod 12, with a set-screw 35 employed for clamping it in place thereon.

60 The tension-bracket 33 is preferably of duplex construction having similarly formed shelf-portions 36 disposed on opposite sides of the hub 34. Each portion 36 of the bracket 33 is provided with an angularly formed arm 37 carrying a guide-hook 38 for the strand y. The inner portion of the arm 37 has an opening 39 therein through which the strand y draws as it leads from the cone C. From the guide-hook 38 the strand y passes between the tension-disks 31 and around the pin 32, and thence draws outwardly therefrom around a second guide-hook 40 on the bracket 33. After the strands y from the whole series of supplies or cones C have been threaded through the tension-devices in the manner as above explained the ends are drawn off to one side as shown in Fig. 3 and carried to the warping machine or other apparatus in which the yarn 100 is to be converted.

65 Due to the high speed at which the strands draw through the tension-devices 30, the unwrapping of the coils from the cones C causes the strands to fly outwardly under centrifugal force, resulting in the ballooning of that portion of the ends extending between the supplies and the tension-devices 30. The ballooning may vary considerably during the unwinding of the yarn, alternately increasing and decreasing as the resistance is lessened or augmented, respectively, at the cone. Frequently, the ballooning becomes excessive and the strand is whipped forwardly toward the tension-device so that it is liable to become entangled on the pins 32 and guide-hooks 38 and 40. Should the strand become caught or entangled in the parts of the tension-devices, further delivery of the end from the creel would be prevented 115 120 125 130

and the yarn strained and broken. In such case the process for which the yarn is being delivered must be stopped to piece up the broken strand or strands. Frequent interruption in the operation of the apparatus from such causes will therefore greatly reduce production and increase the cost of the product. It is therefore desirable to provide the creel with means for preventing excessive ballooning of the strands to eliminate entanglement and breakage of the ends and the present invention provides an improved device for this purpose.

In the preferred form of construction as herein shown the means for preventing excessive ballooning of the yarn in the creel comprises a series of vertically disposed baffle-plates or separators 41 which are arranged in the path of the strands drawing between the cones C and the tension-devices 30. The separators 41 are preferably constructed in the form of rectangular strips of sheet-metal, see Fig. 5, and are perforated along their length to provide a plurality of openings 42 through which the strands are adapted to lead. The openings 42 in the separators 41 may be circular in shape and of generous size to facilitate the threading of the ends therethrough. The separators 41 are hinged to the frame of the creel by means as next described to adapt them to be shifted in position for a purpose as later explained.

As shown in Figs. 3 and 5, each separator 41 is provided with a plurality of U-shaped yoke-members 43 constituting the hinges on which it turns. The hinge-members 43 are preferably constructed from sheet-metal and attached to the metal strip 41 by means of rivets, bolts or the like, the arms of the members being provided with alined openings 44 for receiving the hinge-pins. A separator 41 is disposed at the rear of each vertical series of tension-devices 30, and for the purpose of hingedly mounting them on the creel the forward rods 12 carry brackets 45, one for each of the hinge-members 43 on the separator.

The bracket 45, shown at the right in Fig. 3, has a notched or yoke-shaped portion 46 embracing the rod 12 with a set-screw 47 therein for clamping the bracket to the rod. An arm 48 projecting laterally from the clamp-portion 46 of the bracket 45 is provided with an offset lug 49 adapted to be straddled by the arms of the hinge-members 43 on the separators 41. Preferably, the arm 48 extends outwardly and rearwardly from the rod 12 and the hinge-member 43 of the separator 41 is joined thereto by means of a pin 50 passed through its openings and a hole in the lug 49. The arm 48 terminates in an angularly disposed stop-finger or abutment 51, against which the side of the separator 41 bears when

the parts are positioned as shown by the full lines in Fig. 3. With the separators held in this position the openings 42 therein will aline with the guide-openings 39 of the respective tension-devices 30 arranged adjacent thereto.

Any suitable means may be provided for maintaining the separator 41 in operative position as held against the end of the stop-finger 51, and preferably one or more coiled springs 55 are employed for this purpose. As shown in Figs. 3 and 5, the upper end of the separator 41 is formed with an ear 53 having an opening 54 into which is hooked one end of the spring 55. The opposite end of the spring 55 is anchored to the end of an arm 56 projecting laterally from a collar 57 surrounding the rod 12 and secured in position by means of a set-screw 58.

The cones C or other yarn supplies are applied to the creel from the front, there being sufficient space between the pairs of associated tension-devices 30 to permit the operator to pass the full packages inwardly therebetween. But with the separators 41 arranged in operative position at the rear of the tension-devices the open space between the rods 12 is reduced to such an extent as to prevent the free passage of a full package through the front of the creel. Accordingly, when it is necessary to doff the exhausted packages and re-creel new cones, the separators 41 may be folded rearwardly on their hinges to position them at substantially right-angles to their normal relationship on the rods 12, as shown by full lines in Figs. 1 and 4, and by broken lines in Fig. 3.

As the separators 41 are folded rearwardly their inner edges will engage a step or shoulder 60 on the bracket 45 as shown most clearly in Fig. 3. Inasmuch as the spring 55 is secured to the outer portion of the separator 41, when the separator is folded rearwardly the spring will be carried from one side of the hinge to the other, thereby tending to hold the separators against the step 60. The retention of the separators 41 in both their operative and inoperative positions is therefore automatic, the operator being only required to swing the separator to a slight extent to carry the spring across center.

In the operation of the creel the plurality of ends from the cones C or other supplies are threaded through their respective openings 42 in the separators 41 and thence through the tension-devices 30. The strands are then led to the warper or other machine to adapt them to be drawn off from the supplies by the operation of the process to which they deliver. The separators 41 are so related with respect to the tension-devices 30 that the openings 42 limit the

extent of the whipping or ballooning of the strands *y* when the yarn is drawn off from the cones *C* at a rapid rate, as indicated in the plan view, Fig. 3.

5 The strands are therefore prevented from entangling one with another or from catching on the projecting parts of the creel so that straining or breaking of the yarn from such causes is entirely eliminated. For this 10 reason the process to which the material delivers may be carried on at a faster rate of production and with less wastage of the yarn.

It will be observed that in addition to the 15 advantages above pointed out the present improved creel provides a most compact and efficient device for the purpose specified. The improved apparatus permits warping yarns at a maximum rate of speed, and when 20 it is necessary to stop the machine for the purpose of replenishing the supply, the empty cone-tubes or yarn-receivers may be easily and expeditiously doffed and fresh supplies creel in their place. The improved construction of the creel further provides means 25 for parting the rows or banks of strands passing through the tension-devices to facilitate the finding of broken ends and the operation of piecing them up. The invention 30 therefore greatly increases production and effects further economies in the cost of labor.

While we have herein illustrated and described a preferred form of construction of 35 the improved creel, various modifications may be made in the structure and arrangement of its parts and its method of application to various processes of the textile art without departing from the spirit or scope 40 of the invention.

Therefore, without limiting ourselves to the embodiment of the device as herein shown and described, we claim:

1. In a device of the type specified, the 45 combination of means for supporting a plurality of supply packages, means for guiding the strands delivering from the packages, and means intermediate the packages and the guiding-means and spaced at a distance from each for restricting the ballooning of the strands as they unwind from the packages to prevent interference therebetween or entanglement thereof, said last-named means having circular openings 50 through which the strands draw, and each opening being large enough to permit the strand to play therein to a certain extent to revolve around the edge thereof whereby the ballooning action is damped or quenched 55 to prevent it from becoming excessive.

2. In a device of the type specified, the 60 combination of means for supporting a supply package, and means for governing the unwinding of the strand as it delivers from 65 the package comprising an element formed

with a circular opening through which the strand draws and said opening being of sufficient diameter to allow the strand to play therein to a limited extent to revolve around its edge to reduce the ballooning action of the strand, said governing-means being spaced away from the supply and at a distance from the point to which the strand delivers and adapted to be moved out of operative position to permit access to the supply and its supporting-means. 70

3. In a device of the type specified, the combination of a plurality of supply-holders, tension-devices associated with the supply-holders to adapt the strands to be tensioned thereby as they deliver from the supplies, and means arranged intermediate and located at a distance from both the supply-holders and tension-devices for controlling the ballooning action of the strands, said means being provided with openings through which the strands draw and said openings being large enough to permit the strands to play laterally therein to a limited extent to revolve around the edge of the openings but adapted to restrict the ballooning action thereof in the manner and for the purpose substantially as described. 75

4. A creel comprising supply-holders for supporting a plurality of yarn cops or packages, tension-devices arranged in advance of the supply-holders, and a separator for the multiple strands leading from adjacent packages to the tension-devices comprising a plate-member located intermediate the supply-holders and tension-devices and spaced at a distance from the tension-devices, said plate-member being provided with a series 90 of openings therein through which the strands are adapted to draw, each opening being large enough to permit the strand to play therein to a certain extent to revolve therearound whereby to choke or dampen the ballooning action to prevent it from becoming abnormal. 95

5. In a creel, the combination of supply-holders for supporting a plurality of yarn cops or packages, tension-devices associated with the supply-holders to adapt them to tension the strands drawing off from the supplies, and a separator located intermediate the supply-holders and tension-devices and spaced at a distance therefrom for governing the ballooning action of the strands as they lead from the supplies to the tension-devices, said separator having openings of sufficient size to adapt the strands to revolve therearound and being adapted to be shifted out of operative position to give access to the supplies and their holders in doffing, creeling and piecing up. 100

6. In a creel, the combination of supply-holders for supporting a plurality of supply-cops or packages, tension-devices supported in fixed relation with respect to the supply- 105

- holders for tensioning the strands delivering from the supplies, and separators between the supply-holders and the tension-devices hingedly mounted to adapt them to be set in position to control the ballooning of the strands drawing off from the supplies and to be shifted out of operative position to permit access to the packages and their holders.
7. In a creel, the combination of a plurality of supply-holders for supporting yarn cops or packages, and a hinged separator-plate arranged in advance of the supply-holders and provided with a plurality of openings through which the strands from the supplies lead to restrict their ballooning action as they deliver from the packages, each opening being large enough to permit the strand to play therein and revolve therearound and said separator-plate being located at a distance from the point to which the strands deliver from the supplies and adapted to be swung out of operative position to give access to the supplies and their holders.
8. In a creel, the combination of a plurality of supply-holders arranged in series, a plurality of tension-devices arranged in series opposite the supply-holders and supported in fixed relation with respect thereto, a separator arranged between the supply-holders and the tension-devices and provided with a series of openings through which the strands draw and of such dimension as to allow the strands to play therein to revolve therearound as they lead from the supplies to the tension-devices, and means for hingedly mounting the separator to adapt it to be swung out of the way to give access to the supplies and their holders.
9. In a creel, the combination of a plurality of supply-holders arranged in series, a plurality of tension-devices arranged in series and supported in fixed position in advance of the supply-holders, a separator provided with a series of openings through which the strands lead as they draw from the supplies to the tension-devices, means for hingedly mounting the separator to adapt it to swing out of operative position to give access to the supplies and their holders, and detent-means for normally maintaining the separator in operative position.
10. In a creel, the combination of a framework comprising opposite series of parallel spaced uprights, supply-holders on the rearward uprights for supporting a plurality of yarn cops or packages, tension-devices fixedly supported on the forward uprights, bearings on the forward uprights, separator-plates hinged to said bearings to support them in position in advance of the supply-holders and provided with openings through which the strands lead as they draw from the supplies to the tension-devices, and means for normally maintaining said separator-plates in operative position while adapting them to be swung rearwardly to give access to the supply-holders and the supplies carried thereby.
11. In a creel, the combination of a framework, a plurality of supply-holders mounted on the framework to adapt them to support yarn cops or packages, tension-devices on the framework arranged in alignment with the supply-holders, a separator-plate pivotally mounted on the framework in advance of the supply-holders and spaced at a distance rearwardly of the tension-devices, said separator-plate provided with openings through which the strands are adapted to draw, each opening being large enough to permit the strand to play therein to a limited extent to revolve around its rim, and means for normally maintaining said separator-plate in operative position while adapting it to be folded rearwardly on its hinges to give access to the supply-holders and the packages carried thereby.
12. A device of the type specified comprising means for supporting a yarn cop or package, means arranged in advance of the cop-supporting means to guide the yarn leading from the cop, a separator-plate arranged in advance of the cop-supporting means and spaced at a distance rearwardly from the yarn-guiding means, said separator-plate provided with an opening through which the strand from the package is adapted to draw, said opening being large enough to permit the strand to play therein to follow a circular path around its rim, and means for maintaining said separator-plate in a plane at right-angles to the axis of the cop or package held on the supporting-means while adapting it to be swung into substantially parallel relation with respect to the axis of the package in the manner and for the purpose substantially as described.
13. In a device of the type specified, the combination of a supply-holder for supporting a yarn cop or package, a bearing arranged adjacent the supply-holder, a separator hinged to said bearing to adapt it to be adjusted into operative position with respect to the supply-holder, means for limiting the swinging movement of the separator, and resilient means for maintaining said separator in either operative or inoperative position.
14. The combination with a supply-holder for supporting a yarn cop or package, of a separator having means through which the strand from the package draws to restrict its ballooning action, means for mounting said separator to adapt it to swing into operative or inoperative position with respect to the package held on the supply-holder, stops for limiting the swinging movement of the separator, and a spring for holding the separator.

rator against one stop or the other in accordance with the position to which it is swung.

15. In combination with means for holding a yarn-supply, fixed guiding-means arranged in advance of the supply-holder, and balloon-controlling means arranged in advance of the supply-holder and at a distance rearwardly from the guiding-means, said controlling-means being provided with an annular opening through which the yarn draws of appropriate size to adapt the yarn to revolve around its rim whereby to quench or restrict its ballooning tendency.
- 15 16. In combination with means for holding a yarn-supply, a fixed guide for the yarn arranged at a distance in advance of the supply-holder, a balloon-controlling device arranged in advance of the supply-holder at a distance rearwardly from the fixed guide and having an annular opening through which the yarn leads from the package to the guide, said opening being of appropriate size to allow the yarn to revolve around its rim whereby to quench or restrict its ballooning tendency, and means for mounting said controlling-device to adapt it to be moved out of operative position to give access to the supply.
- 30 In testimony whereof we hereunto affix our signatures.

WILLIAM MARCROFT.
JOHN A. MOLLOY.
